UNITED STATES PATENT OFFICE.

CLYDE F. HUGHES, OF PORTLAND, OREGON.

HOSE-NOZZLE.

1,234,338.

Specification of Letters Patent. Patented July 24, 1917.

Application filed August 14, 1916. Serial No. 114,899.

To all whom it may concern:

Be it known that I, CLYDE F. HUGHES, a citizen of the United States, and a resident of the city of Portland, county of Multnomah, State of Oregon, have invented a new and useful Improvement in Hose-Nozzles, of which the following is a specification.

This invention relates generally to hose nozzles, adapted for emitting a circumferential sheet of water and has particular reference to a nozzle intended for fire hose.

As well known to fire-men, the purpose of the said nozzle is to protect the fire-man holding the nozzle from intense heat by a curtain of water discharged circumferentially by the nozzle. These nozzles are also used to confine a small fire, and keep it from spreading, by enveloping it with a curtain 20 of water.

In order to more effectively accomplish such said purposes it is necessary that the form of the sheet or curtain of water circumferentially discharged by the nozzle be 25 variable from a direction approximately at right angles to the axis of the nozzle, to the form of a cone of greater or lesser cross-section.

My improved nozzle embodies said desirable features.

Its construction and operation are herein-after described, and are fully shown in the accompanying drawings in which:

Figure 1 is a partial longitudinal section of my improved nozzle, the sleeve controlling the direction of the circumferential discharge, being shown in full and dotted lines in its extreme positions.

Fig. 2 is a transverse section on the line 40 2—2 of Fig. 1.

Figs. 3 and 4 are diagrammatic views showing the water deflecting sleeve adjusted to different positions to thereby deflect, at different angles, the sheet of water laterally discharged by the nozzle.

Fig. 5 is a fragmental view showing an alternate detail of construction of the water deflecting portion of said sleeve.

a represents the main body of the nozzle. Said body is provided with interior threads *b* by means of which the nozzle is adapted for attachment to the standard end coupling of a fire hose. A shoulder *c* and packing gasket *d* are provided as a seat for such coupling. Concentric with the body *a* and extending therefrom is a tubular member

e through which the main stream normally flows. Said tubular member is provided with a valve, the handle of which is indicated by *f* and this valve forms a means by 60 which the flow, through the said tubular member *e*, may be regulated or entirely cut off. The inner end of the tubular member, is connected with the body *a* by the radial web members *g*.

It is to be noted that these web members are made with converging sides, the purpose of which will hereafter be pointed out.

The tubular member *e* is also provided with an exterior flaring web *h* the base *i* 70 of which is concaved and polished. The outer end of the body *a* is made with an annular lip *j*, so constructed as to provide an annular opening *k* between the lip *j* and web *h*, which opening forms a circumferential port for the curtain stream.

The rims of the web *h* and lip *j* are beveled so as to form a conical valve seat. The body *a* is provided with an external thread *m*, and mounted on said threaded body is 80 a longitudinally movable water deflecting member. For the purpose of convenience, this deflecting member is made in two parts, *i. e.*, a base ring *n* and a deflector *o*. The latter is rigidly attached to the base ring *n* 85 by the screws *q*.

The deflector is made with a conical bore *r*, the surface of which is adapted to seat on the rim of the circumferential port of the nozzle. Whenever the screws *q* are removed, the deflector piece *o* may be removed and the valve seat thus ground to a true surface. The outer end of the deflector, is bowl shaped in form, comprising a concave portion blending into an outwardly extending convex surface, as shown by *s* in Fig. 1.

The operation of my device is as follows:

When the curtain stream is not to be used, the deflector is moved to the position shown in the full lines of Fig. 1. The circumferential port *k* will then be entirely closed, and the main outlet may be used in the customary manner. When the nozzle is used for fighting fire at close range, the deflector *s* is moved to the position shown 105 in the broken lines of Fig. 1.

The circumferential port *k* will then be entirely open and a cylindrical, conical or lateral water curtain will be thrown from said nozzle, according to the adjustment of 110 the deflector *s*.

The convergence of the sides of the web

member *g* operates to close any break in the curtain of water discharged through the circumferential port which might arise from the passage of the water around the webs.

5 The passage-way from the hose to the circumferential port *k* is carefully designed so as to gain highest efficiency from the pressure and velocity heads of the water.

By the described construction, arrangement and operation of parts the circumferential curtain of water may be varied so as to serve as a fender for the fireman holding the nozzle, or to envelop a particular spot in which a fire is burning and confine the fire to that spot. The latter action is always desirable in fighting a fire, and a curtain of water is most effective for that purpose, while the discharge from an ordinary nozzle frequently throws an undue volume of water on the fire, and in this way does much avoidable damage. The adjustment of the deflector *s* for the purpose of throwing the curtain of water in the form of a cylinder or a cone of greater or lesser cross-section is represented in Figs. 3 and 4.

In Fig. 5, I have shown an alternate construction for the deflector. In this view, the deflecting surface is made with a series of conical plane surfaces, *t*, instead of the curved surface shown in the other views.

I claim:—

1. In a nozzle of the character described, the combination of a chambered body provided with a rim and a valve-controlled axial tubular member the inner end of which extends into the body, such member being made with a circumferential flaring deflecting flange, a sleeve longitudinally movable on the extremity of said body, the extremity of the sleeve being provided with a bowl-shaped water deflecting piece including a rim of substantial width the inner face of which deflecting piece is substantially concaved at the base, then cylindrical, and convex toward the rim, the rim of the body and the flange of the tubular member being adapted to provide a circumferential port, and said sleeve having a portion adapted to close said port when the sleeve is in one position.

2. In a nozzle of the character described, the combination of a chambered body provided with a rim and a valve-controlled axial tubular member the inner end of which extends into the body, such member being made with a circumferential flaring flange having a concave deflecting surface, a sleeve longitudinally movable on the extremity of

said body, the extremity of the sleeve being provided with a bowl-shaped water deflecting piece including a rim of substantial width the inner face of which deflecting piece is substantially concaved at the base, then cylindrical, and convex toward the rim, the rim of the body and the flange of the tubular member being adapted to provide a circumferential port, and said sleeve having a portion adapted to close said port when the sleeve is in one position.

3. In a nozzle of the character described, the combination of a cylindrical chambered body provided with a rim and a valve-controlled axial tubular member the inner end of which extends into the body, the periphery of such inner end being made conical to widen the space between the inner end opposed faces of the body and said member, such member being made with a circumferential flaring deflecting flange, a sleeve longitudinally movable on the extremity of said body, the extremity of the sleeve being provided with a bowl-shaped water deflecting piece including a rim of substantial width the inner face of which deflecting piece is substantially concaved at the base, then cylindrical, and convex toward the rim, the rim of the body and the flange of the tubular member being adapted to provide a circumferential port, and said sleeve having a portion adapted to close said port when the sleeve is in one position.

4. In a nozzle of the character described, the combination of a cylindrical chambered body provided with a rim and a valve-controlled axial tubular member the inner end of which extends into the body, the periphery of such inner end being made conical to widen the space between the inner end opposed faces of the body and said member, such member being made with a circumferential flaring flange having a concave deflecting surface, a sleeve longitudinally movable on the extremity of said body, the extremity of the sleeve being provided with a bowl-shaped water deflecting piece including a rim of substantial width the inner face of which deflecting piece is substantially concaved at the base, then cylindrical, and convex toward the rim, the rim of the body and the flange of the tubular member being adapted to provide a circumferential port, and said sleeve having a portion adapted to close said port when the sleeve is in one position.

CLYDE F. HUGHES.
